UNITED STATES PATENT OFFICE.

HENRY MÜLLER, OF WAHREN, NEAR LEIPSIC, GERMANY, ASSIGNOR TO
THE POLYPHON WERKE, OF SAME PLACE.

MECHANICAL MUSICAL INSTRUMENT.

SPECIFICATION forming part of Letters Patent No. 657,560, dated September 11, 1900.

Application filed September 15, 1898. Serial No. 691,035. (No model.)

To all whom it may concern:

Be it known that I, HENRY MÜLLER, a subject of the Emperor of Germany, residing at Wahren, near Leipsic, Saxony, Germany, 5 have invented certain new and useful Improvements in Mechanical Musical Instruments, of which the following is a full, clear, and exact description.

The present invention relates to that class 10 of mechanical musical instruments in which the effect of the violin tone is produced by a moving endless band, onto which the strings are pressed by mechanical means by the aid of a note disk sheet or the like.

15 The invention consists of the details of construction hereinafter set forth, and particularly pointed out in the claim.

In order to render the present specification more easily intelligible, reference is had to 20 the accompanying drawings, in which similar letters of reference denote similar parts throughout the several views.

Figure 1 is a sectional elevation of the instrument; Fig. 2, a plan; Fig. 3, a detail sectional elevation showing the string-operating mechanism; Fig. 4, a detail side elevation showing the string depressed; Figs. 5 and 6, a cross-section and a plan of the bow-supporting bridge or comb; Figs. 7 and 8, similar 25 views of a modified form of bridge; Figs. 9 and 10, an elevation and a plan of the note defining or stretching mechanism for the strings; Figs. 11 and 12, a modified form of the device, and Figs. 13 and 14 a similar elevation and a 30 35 sectional plan of a further modification.

Referring to Figs. 1 to 4, on the sounding-board V of the instrument are supported the strings S by means of pins s and pegs W, the latter serving to tune the strings. The strings 40 S are supported on the bridges S' and S², an intermediate bridge S² being adjustably supported below the strings and serving to produce the required note when the string S is depressed onto the moving band or bow B, 45 which for the purposes of this specification will be called the "bow," and is of suitable material to produce a musical sound when the strings are brought into contact therewith. In order to properly support the bow 50 B, the same runs over the fixed table T and is an endless band supported on suitable

rolls 3 and 4 and driven from any suitable source of power by means of a cord or the like 5, which may be guided on pulleys 1 and 2. g indicates the note sheet or disk, supported to move in a horizontal plane above the strings and having downwardly-extending teeth Z, adapted to depress a lever H, pivotally mounted at x. The tooth or teeth of the note-sheet disk or roll (as will be 60 readily understood a roll could be substituted, as indicated at Fig. 3) contact with an upwardly-extending nose K of the lever H, depressing the latter and causing its downwardly-extending arm S⁴ to depress the corresponding string S onto the bridge S² and the moving bow B, thus forming and producing the required note. The mechanism for moving the note disk sheet or roll is not shown, as any suitable means may be employed. M M 70 indicate supporting-beams for the note-sheet; N, a guiding-clamp for the note sheet or disk holder, which reaches to the disk-supporting point C. This mechanism is, however, not shown, since the same forms no part of the 75 present invention. In order to keep the bow tight, a spring-lever h is pivotally mounted at y on the beam M and has a roll R, which is spring-pressed against the bow B by means of the spring F. L is a ledge which serves 80 to limit the upward movement of the levers H, which are returned to their initial position after having operated the string by means of the elasticity of the latter. As indicated at Fig. 3, instead of the sheet g a roll g' may be 85 employed. The stop-ledge L is so adjusted that the string after having been vibrated will be damped by the arms S⁴ of lever H still resting on it.

Instead of a full stationary table underneath the bow a comb-like table T⁶ may be employed, as shown at Figs. 5 and 6.

In order to accurately determine the length of string necessary to produce the required note, a bar R⁹ is provided having upwardly-extending pins 6, against which the strings are stretched, Figs. 9 and 10. These pins may also be additionally stayed or supported by a top bar R', Figs. 11 and 12. These pins serve to sharply define the length of string which 95 is vibrated by the bow.

As shown at Figs. 7 and 8, the bow may be

supported on a **U**-shaped bar L^X , having rolls W^X instead of the full bridge, and instead of the pins 6 the bar R^0 may be provided with orifices P^X for the strings, Figs. 13 and 14, the 5 said bar in this case being made of one piece of material. The tone may be produced by tubes or rods instead of strings. The bar having pins for accurately defining the length of the string to be vibrated to produce the 10 note is fixed in the instrument in such a manner as to cause the strings to be stretched at an angle on the said pins, as will be evident from Figs. 10 and 12.

I claim as my invention—

15 In a mechanical musical instrument of the class specified having a set of strings and a

bow moving in a direction transversely to the same and means for depressing the string down onto the moving bow, the combination of a stationary table to support the said bow and 20 means for sharply defining the length of string to be depressed consisting of a bar having a series of vertically-located pins or ledges around which the strings are stretched substantially as described. 25

In witness whereof I have hereunto set my hand in presence of two witnesses.

HENRY MÜLLER.
